DESIGN FOR A MERCHANTISE-TAG.

Design No. 12,944, dated May 23, 1882.

UNITED STATES PATENT OFFICE.

SABIN L. SAYLES, OF KILLINGLY, CONNECTICUT.

DESIGN FOR A MERCHANDISE-TAG.

SPECIFICATION forming part of Design No. 12,944, dated May 23, 1882.

Application filed April 12, 1882. Term of patent 3½ years.

To all whom it may concern:

Be it known that I, SABIN L. SAYLES, a citizen of the United States, residing at Killingly, in the county of Windham and State of Connecticut, have invented and produced a new and original Design for Merchandise-Tags for Cloths, of which the following is a specification, reference being had to the accompanying drawing, forming a part thereof.

10 The leading and novel features of my design are as follows: Through two slots running parallel to the angularly cut-off upper corners of a border-line inclosing a rectangular space are inserted small bunches of some flower or shrub. 15 Within the surface inclosed by the above-mentioned border-line are two sunflowers upon short stems, one lapping over and partially concealing the other. These flowers are upon a dark ground of circular form, and the dark 20 ground is bordered by a single circle running a short distance from its edge. Above the circle-inclosed flowers may or may not be the word "Æsthetic." I do not wish to be restricted to the use of this word, although I 25 prefer to use it.

In the accompanying drawing, A A are the flowers (in this particular instance the well-known cat-tail) inserted in slots. B B are the cut-off corners of the border-line of the tag. C C are the sunflowers, and D the circular border surrounding the dark ground on which they are thrown.

I am aware that sunflowers are not new as ornamental designs, and I do not therefore claim them, broadly; but

What I claim is—

The design for a tag for cloths or like merchandise, as herein shown and described, the same consisting of sunflowers on a circular dark ground bordered by a single circle, and 40 bunches of plants inserted in slots running parallel to cut-off corners of a border-line near the edge of the tag.

SABIN L. SAYLES.

Witnesses:

ALLEN TENNY,
LUCIUS BROWN.
